UNITED STATES PATENT OFFICE

121,779

DESIGN FOR A BOWLING GAME APPARATUS

Irven H. Wilsey, Chicago, Ill.

Application November 9, 1939, Serial No. 88,157

Term of patent 14 years

To all whom it may concern:

Be it known that I, Irven H. Wilsey, a citizen of the United States, residing at Chicago, in the county of Cook and State of Illinois, have invented a new, original, and ornamental Design for a Bowling Game Apparatus, of which the following is a specification, reference being had to the accompanying drawing, forming a part thereof.

In the drawing, Fig. 1 is a perspective view of the bowling game apparatus embodying my new design;

Fig. 2 is a side elevational view of the same; and

Fig. 3 is a rear elevational view of the same.

I claim:

The ornamental design for a bowling game apparatus, as shown.

IRVEN H. WILSEY.
